UNITED STATES PATENT OFFICE.

STEPHEN EDWARD JACKMAN, OF NEW YORK, N. Y.

RAILWAY.

No. 846,209.

Specification of Letters Patent.

Patented March 5, 1907.

Application filed June 20, 1906. Serial No. 322,540.

To all whom it may concern:

Be it known that I, STEPHEN EDWARD JACKMAN, a citizen of the United States, and a resident of the city of New York, Coney Island, borough of Brooklyn, in the county of Kings and State of New York, have invented a new and Improved Railway, of which the following is a full, clear, and exact description.

10 The invention relates to switch-back or gravity railways, such as are used in pleasure-resorts, exhibition-grounds, and the like.

15 The object of the invention is to provide a new and improved railway having a continuous track for cars to travel on, the track being provided with deep dips in the several courses to render the ride exceedingly interesting and exciting to the passengers in the cars.

20 The invention consists of novel features and parts and combinations of the same, which will be more fully described hereinafter and then pointed out in the claims.

25 A practical embodiment of the invention is represented in the accompanying drawings, forming a part of this specification, in which similar characters of reference indicate corresponding parts in both the views.

Figure 1 is a plan view of the improvement, and Fig. 2 is a side elevation of the same.

The continuous track of the railway has a station portion A, leading at one end to the lower end of the upwardly-inclined uptrack B and connecting at its other end with the terminal of the homestretch C, and between the top of the uptrack B and the beginning-point of the homestretch C extends the intermediate loop-section D. The station portion A is approximately level and is preferably built on the ground and is arranged to afford a desirable location for the station E to facilitate the embarkation and disembarkation of the passengers in the cars F traveling over the continuous track. The uptrack B, the homestretch C, and the intermediate or loop section D are shown supported on a suitable framework B; but this part of the device is not material, as the continuous track may be located in a building built for the purpose. The uptrack B is provided with an endless propelling-chain H, having spaced cross-bars for engaging projections or arms depending from the bottom of the car or vehicle F traveling over the continuous track, and the said endless chain H is driven by a suitable mech-

anism from a power-house I, preferably arranged within the track, as indicated in the drawings. The intermediate or loop section D consists of a plurality of convolutions, the 60 side arms D' and D² of which are disposed in different vertical planes on the side of the structure on which the homestretch C is located. The side arms D' and D² of the convolutions are provided with dips D³ D⁴, which 65 are wholly independent of each other on account of having the side arms D' D² disposed in different vertical planes, as before mentioned and shown in Fig. 1. Thus the dips D³ and D⁴ may be of any desired depth, 70 as the dip of one side arm does not interfere or come in contact with the adjacent side arm and its dip. It will also be noticed by reference to Fig. 1 that the side arms D' D² are located in vertical planes inside of the 75 homestretch C, so that the latter can uninterruptedly pass back to the station portion A to complete the continuous track. By reference to Fig. 2 it will be seen that the dip D³ extends to a depth lower than the lowest 80 portion of the following side arm D², and the dip D⁴ of the side arm D² extends below the middle portion of the homestretch C—that is, reaches clear down to the ground.

From the foregoing it will be seen that by 85 the arrangement described a very long ride is provided which will prove highly exciting and interesting to the passengers in the cars F, traveling over the track.

It is understood that passengers desiring 90 to enjoy a ride over the railway embark at the entrance side of the station portion A, and the car F thus filled with passengers is pushed by an attendant to the bottom of the uptrack B, so that the endless chain H now 95 engages the car F and pulls the same up the uptrack B, and finally the said chain H disengages the car when reaching the uppermost point of the uptrack and the starting-point of the descent at the beginning of the intermediate or loop section D. The car now runs by its own gravity over the intermediate or loop section D to the homestretch C and down the same back to the station portion A at the exit side thereof so that the passengers can disembark from the car, and as soon as the latter is empty it is pushed to the other side of the station and the above operation is repeated.

By the arrangement described the cars continually travel over the endless continuous track and very little time is lost in the em-

barkation and disembarkation of the passengers. Hence many cars can be run simultaneously on the track, spaced suitable distances apart, and hence a large revenue can 5 be derived from the running of the railway in a comparatively short time.

Having thus described my invention, I claim as new and desire to secure by Letters Patent—

- 10 1. A railway having a continuous track consisting of an uptrack, a homestretch leading back to the bottom of the uptrack, and a loop-section connecting the upper end of the said uptrack with the beginning of the 15 said homestretch, the said loop-section having a plurality of convolutions, of which the side arms on one side of the loop-section are disposed in different vertical planes and inward from the said homestretch, the said side arms having dips, of which the dips of one side 30 arm may have any desired depth relative to the depth of the dips of an adjacent side arm and the said homestretch.
- 20 2. A railway having a continuous track

consisting of an uptrack, a homestretch leading back to the bottom of the uptrack, and a loop-section connecting the upper end of the said uptrack with the beginning of the said homestretch, the said loop-section having a 25 plurality of convolutions, of which the side arms on one side of the loop-section are disposed in different vertical planes and inward from the said homestretch, the said side arms having dips, of which the dips of one side 30 arm may have any desired depth relative to the depth of the dips of an adjacent side arm and the said homestretch.

In testimony whereof I have signed my name to this specification in the presence of 35 two subscribing witnesses.

STEPHEN EDWARD JACKMAN.
